Primary Examiner — Brett Miller(74) *Attorney, Agent, or Firm* — Patterson Theunte Pedersen, P.A.(57) **CLAIM**

I claim the ornamental design for a rotisserie grill, as shown and described.

DESCRIPTION

FIG. 1 is a front perspective view of a rotisserie grill, according to an embodiment.

FIG. 2 is a rear perspective view of the rotisserie grill depicted in FIG. 1.

FIG. 3 is a front elevational view of the rotisserie grill depicted in FIG. 1.

FIG. 4 is a right side elevational view of the rotisserie grill depicted in FIG. 1.

FIG. 5 is a left side elevational view of the rotisserie grill depicted in FIG. 1.

FIG. 6 is a rear elevational view of the rotisserie grill depicted in FIG. 1.

FIG. 7 is a top plan view of the rotisserie grill depicted in FIG. 1; and,

FIG. 8 is a bottom plan view of the rotisserie grill depicted in FIG. 1.

The broken lines in the drawings illustrate portions of the rotisserie grill that form no part of the claimed design.
